UNITED STATES PATENT OFFICE

126,372

DESIGN FOR A MERCHANTISE DISPLAY RACK

José Trojan, Chicago, Ill., assignor to Owen Housholder and David C. Cohen, copartners, doing business as Crystal Manufacturing Co., Chicago, Ill.

Application January 27, 1941, Serial No. 98,409

Term of patent 3½ years

To all whom it may concern:

Be it known that I, José Trojan, a citizen of the United States, residing at Chicago, in the county of Cook and State of Illinois, have invented a new, original, and ornamental Design for a Merchandise Display Rack, of which the following is a specification, reference being had to the accompanying drawing, forming part thereof.

chandise display rack embodying my new design;

Figure 2 is a top plan view thereof; and

I claim:

The ornamental design for a merchandise display rack, substantially as shown.

JOSÉ TROJAN.
